VALVE

Otto J. Kuenhold, Shaker Heights, Ohio

Application November 10, 1931, Serial No. 574,147

7 Claims. (Cl. 137—153)

My invention relates to a valve structure, and particularly, to a valve structure for controlling the flow of fluid fuel to the burner of a domestic heating plant or like apparatus.

5 It is one object of my invention to provide a fluid fuel control valve of the graduated action type with the valve so constructed and the parts so arranged that the valve gate or closure element will automatically move to cut off the fluid fuel supply to the burner with a quick or relatively rapid action when the valve has been mechanically closed to a point where less fluid fuel is passed to the burner than the burner can safely use.

15 Another object of my invention is to provide a fluid fuel control valve so constructed and with parts so arranged that the gate or closure, after initiation of movement toward open position, will move to a position with a quick or relatively rapid action to permit enough fluid fuel to pass to the burner so that the burner may be promptly, completely and safely ignited from an independent pilot burner, without backfiring or delayed ignition.

20 Still another object of my invention is to provide a fluid fuel control valve wherein the amount of fluid fuel supplied to a burner at which the valve gate or closure will move to complete closed position with a quick or relatively rapid action, as well as the amount of fluid fuel passing to the burner when the gate or closure moves to open position with a quick or relatively rapid action can each be separately adjusted.

25 A further object of my invention is to provide a fluid fuel control valve which, after being once adjusted, will completely cut off the supply of fluid fuel to the burners with a quick or relatively rapid action when closed to such an extent that the flame jets issuing from the burners are reduced to minimum safe height regardless of whether one or more than one burner is in operation. That is, the complete snap action closure is not determined by a certain minimum volume of fluid fuel passed by the valve, but rather by a certain minimum volume of fluid fuel per burner. The control valve is such as to automatically adjust itself, as to the total volume of fluid fuel passed by the valve, according to the number of burners which may be in operation at 30 the time. This is accomplished by having the complete closure determined by the fluid fuel back pressure in the outlet chamber of the valve.

35 Various other objects of my invention may be seen in the following description and one embodiment of my invention may be seen in the ac-

companying drawing wherein similar characters of reference designate corresponding parts, and wherein:

Fig. 1 is a view, partly in section and partly in elevation, showing a valve structure constructed in accordance with my invention; Fig. 2 is a sectional view taken on the line 2—2 of Fig. 1; and Fig. 3 is a view showing a modified form of the lost motion connection in the valve operating levers.

40 In the drawing, I have shown one embodiment of my invention as comprising a valve consisting of a casing 1 having a cover 2 therefor and secured thereto by means of screw bolts, or the like, 15. The casing 1 is provided with a threaded opening 4 adapted to receive a fluid fuel inlet conduit 5 and leading to an inlet chamber 6. Such casing is also provided with a threaded opening 7 adapted to receive one end of a fluid fuel supply conduit 1' leading to burner elements (not 20 shown) which provide a restricted fuel outlet and produce back pressure in the outlet chamber, the opening 7 leading from an outlet chamber 8 which extends over substantially the entire circumferential area of the valve casing 1. A port 25 9 connects the fluid fuel inlet chamber 6 with the fluid fuel outlet chamber 8.

45 In accordance with my invention, a gate or closure 10 is provided for the inlet port 9 and is adapted to open or close communication between the inlet chamber 6 and the outlet chamber 8 as desired, and this gate or closure is attached to or forms a part of a diaphragm 11. This diaphragm provides a means for automatically opening or closing communication between the inlet 35 chamber 6 and outlet chamber 8 under certain conditions, as will be hereinafter described. A mechanical means is provided for moving the gate or closure 10 toward or away from the port 9 which consists of a stem 12 attached to the 40 diaphragm 11 that is held between the coincidental surfaces 13 and 14 of the casing cover and casing when the parts are in assembled relation as shown, and to the valve gate or closure 10 as shown in Fig. 1. The uppermost end of the stem 45 12 is pivotally attached to an operating lever 15 as at 16, the operating lever 15 being operatively mounted on the cover 2 as at 17 and having adjustably mounted thereon a weight 18 that may be held in any of a number of positions of adjustment along the length of the operating lever 15 by means of a set screw 19 or the like.

50 Suitable means is also provided for moving the operating lever 15 about the pivot 17 to move the valve gate or closure 10 toward or away 55

from the port 9 which consists of an operating lever 20 having its lowermost end operatively connected with the free end of the operating lever 15 by means of a lost motion connection. As shown in Fig. 1, the lowermost end of the operating lever 20 is slotted as at 21, the slotted portion being adapted to receive a pin 22 extending outwardly from the free end of the operating lever 15. A screw bolt 23 extends through the lowermost end of the operating rod 20 and has its free end disposed in the slotted portion 21 of the operating rod 20. Thus, a lost motion connection is provided between the operating rod 20 and the operating lever 15. The uppermost end of the operating rod 20 is pivotally connected as at 25 to one free end of a lever 26, pivotally mounted as at 27, the opposite end of the lever 26 being very slowly movable upwardly or downwardly by thermostatically operating means 29 disposed, in this instance, in conjunction with a furnace structure 30 that is diagrammatically shown.

In the operation of this valve structure, it will be noted that the diaphragm 11 is exposed on its under side to the fluid fuel pressure existing in the outlet chamber 8 which extends under the entire diaphragm so that when the diaphragm is pushed downwardly it is resisted by the existing fluid fuel pressure in the fluid fuel outlet chamber 8. Of course, downward movement of the diaphragm 11 is accomplished by downward movement of the operating rod 20, and the operating lever 15 by operation of the lever 26 by the thermostatic control means 29, this downward movement of the diaphragm taking place when the condition of the furnace requires that the flow of fluid fuel to the burner elements (not shown) be reduced or cut off.

Downward movement of the diaphragm 11 and gate or closure 10 which is attached thereto and forms a part thereof reduces the amount of fluid fuel flowing into the outlet chamber through the port 9 and hence reduces the fluid fuel pressure in the outlet chamber and the port pressure against the fluid valve member or diaphragm 11. When the fluid fuel pressure in the outlet chamber 8 is reduced to a point where the total upward pressure against the floating valve member or diaphragm 11 is less than the downward force due to the weight of the valve member itself plus the effect of the weight of the operating lever 15 and the adjustable weight 18, the floating valve member or diaphragm and the closure 10 move downwardly with a quick or relatively rapid action to instantly close off the communication between the inlet 6 and outlet 8 by closing the port 9. This sudden closure of the port 9 is permitted by the lost motion connection between the operating rod 20 and the operating lever 15 hereinbefore described. As soon as the communication between the inlet chamber 6 and outlet chamber 8 is closed off, the fluid fuel pressure in the outlet chamber 8 drops to zero as the fluid fuel is drained off to the burner which permits a tight closure of the inlet port 9 due to the weight of the mechanism on the gate or closure 10.

Reversely, when the operating rod 20 is moved upwardly by the action of the thermostatic control means 29, the lost motion between the operating rod 20 and operating lever 15 is first taken up, the weight of the valve mechanism holding the valve gate or closure 10 against its seat on the port 9 to prevent communication between the inlet chamber 6 and the outlet chamber 8. Then,

when the operating rod 20 has moved upwardly sufficiently to begin lifting of the operating lever 15 and hence the floating valve member or diaphragm 11 and gate or closure 10, fluid fuel rushes out into the outlet chamber 8 and instantly creates a pressure in the outlet chamber which is effective to lift the floating valve member or diaphragm 11, gate or closure 10, pin 12, and operating lever 15 upwardly as far as the lost motion connection hereinbefore described between the operating lever 15 and the operating rod 20 will permit. This opens the port 9 sufficiently to permit enough fluid fuel to pass through the outlet chamber 8 to the burner elements (not shown) to permit complete ignition of the burner elements from an independent pilot burner without backfire or delay in ignition. Of course, the extent of upward movement of the valve gate or closure 10 and cooperating parts by a quick or relatively rapid action may be controlled by adjustment of the screw 23 to vary the degree of lost motion in the connection between the operating rod 20 and the operating lever 15.

As shown, a rigid plate 31 is provided above the diaphragm 11 to increase the area of the diaphragm upon which fluid fuel pressure can be effective to raise the diaphragm, it being essential that the effective area of the diaphragm multiplied by the fluid fuel back pressure at which the diaphragm is to move downwardly with a quickly or relatively rapid action to close the inlet port is equal to the weight of the diaphragm plus the effect of the adjustable weight 18, the operating lever 15, and associated parts in moving the diaphragm downwardly, that is, the effective area of the diaphragm and hence the opposing weights must be in such relation to each other that the weights alone can hold the valve gate or closure 10 in closed position against any ordinary inlet pressure, otherwise quickly or relatively rapid action of the valve gate or closure will not be obtained.

My invention also contemplates the provision of means supplemental to the adjustable weight 18 hereinbefore described for varying the time, in accordance with the amount of fluid fuel passing through the port 9, at which quickly or relatively rapid opening or closing of the gate or closure 10 takes place. As shown in Fig. 1, a port 32 is provided in the outlet chamber 8 through which fluid fuel must pass from the outlet port 9 to the pipe 7, and a valve 33 that may be moved into and out of proximity with the port 32 through the screw thread support 33a of its stem is provided for varying the degree of opening of the port 32 as will be readily apparent. Thus, a means is provided for increasing or decreasing the rate of escapement of fluid fuel from the outlet chamber 8 in proportion to the rate of flow of the fluid fuel through the inlet port 9 to the outlet chamber so that if it is desired to have the quickly or relatively rapid opening of the valve 10 taking place sooner or later after opening of the port 9 it is merely necessary to increase or decrease the size of the port 32 by adjustment of the valve 33. This adjustment together with adjustment hereinbefore described by the weight 18, provides a valve in which the quickly or relatively rapid action of the valve may be regulated to a very fine degree. In other words, this adjustment makes it possible to materially reduce the pressure at the burners as compared to the fuel pressure at the fuel inlet port.

Referring to Fig. 3 of the drawings, I have

shown a modified form of lost motion connection between the operating lever 15 and the operating rod 20. In this figure, springs 34 and 35 are disposed in the slot 21 above and below the pin 22 respectively. One end of the lowermost spring 35 rests in a cup 36 carried by the set screw 23 whereby the compression on the springs 34 and 35 may be varied as desired by adjusting the set screw 23.

With this type of lost motion connection, assuming that the valve gate or closure 10 is seated to close off the inlet port 9, upward movement of the operating rod 20 to raise the valve gate or closure will result in compression of the lowermost spring 35. Then, when the gate or closure 15 is raised sufficiently to permit enough fluid fuel to escape and exert a pressure on the under side of the diaphragm 11, the pressure on the underside of the diaphragm plus the expanding force of the spring 35 will move the valve gate or closure upwardly with a quick or relatively rapid action. That is, with the assistance of the spring 35, the pressure on the under side of the diaphragm 11 need not be so great as when pressure alone is used.

23 Reversely, assuming the valve gate or closure 10 to be in full open position, downward movement of the operating rod 20 to move the gate or closure toward the inlet port 9 will result in compression of the spring 34 to store energy which, when the fluid fuel escaping from the port 9 is reduced to a certain degree, will, in this instance, in combination with the weight 18 and lifting mechanism as previously described in connection with the closing movement of the valve, move the gate or closure to a closed position with a quick or relatively rapid action.

In the above construction, I have provided a valve structure, that is particularly adapted to the control of fluid fuel supply to a burner structure, which will automatically close off all fuel supply to the burner structure with a quick or relatively rapid action when the normal fuel supply to the burner structure is less than is necessary to permit safe operation of the burners without danger of the flame jets being extinguished due to smothering or insufficient fuel supply. Likewise, the fluid fuel control valve structure is such that, immediately after initiation of opening movement of the valve gate or closure, this valve gate or closure will move to open position with a quick or relatively rapid action far enough to permit sufficient fluid fuel to flow to the burner structure so that the burners may be ignited from an independent pilot burner without backfire or delayed ignition. Various other advantageous features will be readily apparent.

What I claim is:

1. A valve structure, comprising a valve casing having a gas inlet chamber and a gas outlet chamber, inter-communication of which is effected by a port therebetween, a movable abutment in said casing and constituting a closure for said port, said abutment being of greater area than said port and also constituting at least a part of a wall of said outlet chamber, the gas pressure on one face of said abutment constituting a varying force biasing said abutment for movement in port-opening direction, means constituting a constant force biasing said abutment for movement in port-closing direction, said constant biasing force being greater than the force of the gas pressure against that portion of said abutment which constitutes a closure for said port, and mechanical means having a lost motion connection therein and operatively connected with said abutment for effecting, when actuated, limited movement of said abutment relative to said port, and means for actuating said mechanical means, the parts being so constructed and arranged that when limited movement of said abutment relative to said port has been effected by actuation of said mechanical means, one of said abutment biasing forces preponderates over the other and said preponderating force, by taking up the lost motion in said mechanical means, is effective to continue such movement of said abutment relative to said port.

2. A valve structure, comprising a valve casing having a gas inlet chamber and a gas outlet chamber, inter-communication of which is effected by a port therebetween, a movable abutment in said casing and constituting a closure for said port, said abutment being of greater area than said port and also constituting at least a part of a wall of said outlet chamber, the gas pressure on one face of said abutment constituting a varying force biasing said abutment for movement in port-opening direction, means constituting a constant force biasing said abutment for movement in port-closing direction, said constant biasing force being greater than the force of the gas pressure against that portion of said abutment which constitutes a closure for said port, and mechanical means having a lost motion connection therein and operatively connected with said abutment for effecting, when actuated, limited port-opening movement of said abutment, and means for actuating said mechanical means, the parts being so constructed and arranged that when limited port-opening movement of said abutment has been effected by actuation of said mechanical means, the biasing force of said gas pressure is increased sufficiently to preponderate over said other biasing force and said preponderating gas pressure force, by taking up the lost motion in said mechanical means, is effective to complete port-opening movement of said abutment.

3. A valve structure, comprising a valve casing having a gas inlet chamber and a gas outlet chamber, inter-communication of which is effected by a port therebetween, a movable abutment in said casing and constituting a closure for said port, said abutment being of greater area than said port and also constituting at least a part of a wall of said outlet chamber, the gas pressure on one face of said abutment constituting a varying force biasing said abutment for movement in port-opening direction, means constituting a constant force biasing said abutment for movement in port-closing direction, said constant biasing force being greater than the force of the gas pressure against that portion of said abutment which constitutes a closure for said port, and mechanical means having a lost motion connection therein and operatively connected with said abutment for effecting, when actuated, limited port-closing movement of said abutment, and means for actuating said mechanical means, the parts being so constructed and arranged that when limited port-closing movement of said abutment has been effected by actuation of said mechanical means, the biasing force of said gas pressure is so reduced that said other biasing force preponderates thereover and said preponderating force, by taking up the lost motion in said mechanical means, is effective to complete port-closing movement of said abutment.

4. A valve structure, comprising a valve casing

- having a gas inlet chamber and a gas outlet chamber, inter-communication of which is effected by a port therebetween, a movable abutment in said casing and constituting a closure for said port, said abutment being of greater area than 5 said port and also constituting at least a part of a wall of said outlet chamber, the gas pressure on one face of said abutment constituting a varying force biasing said abutment for movement 10 in port-opening direction, means constituting a constant force biasing said abutment for movement in port-closing direction, said constant biasing force being greater than the force of the gas pressure against that portion of said abutment 15 which constitutes a closure for said port, and mechanical means having a lost motion connection therein and operatively connected with said abutment for effecting, when actuated, limited port-opening movement and limited port-closing 20 movement of said abutment, and means for actuating said mechanical means, the parts being so constructed and arranged that when limited port-opening movement of said abutment has been effected by actuation of said mechanical 25 means, the biasing force of said gas pressure is increased sufficiently to preponderate over said other biasing force and said preponderating gas pressure force, by taking up the lost motion in said mechanical means, is effective to complete port-opening movement of said abutment, and when 30 port-closing movement of said abutment has been effected by actuation of said mechanical means, the biasing force of said gas pressure is so reduced that said other biasing force preponderates 35 thereafter and said preponderating force, by taking up the lost motion in said mechanical means, is effective to complete port-closing movement of said abutment.
5. A valve structure, comprising a valve casing 40 having a gas inlet chamber and a gas outlet chamber, inter-communication of which is effected by a port therebetween, a movable abutment in said casing and constituting a closure for said port, said abutment being of greater area 45 than said port and also constituting at least a part of a wall of said outlet chamber, the gas pressure on one face of said abutment constituting a varying force biasing said abutment for movement in port-opening direction, means constituting a constant force biasing said abutment 50 for movement in port-closing direction, said constant biasing force being greater than the force of the gas pressure against that portion of said abutment which constitutes a closure for said

port, and mechanical means having an adjustable lost motion connection therein and operatively connected with said abutment for effecting, when actuated, limited movement of said abutment relative to said port, and means for actuating said mechanical means, the parts being so constructed and arranged that when limited movement of said abutment relative to said port has been effected by actuation of said mechanical means, one of said abutment biasing 10 forces preponderates over the other and said preponderating force, by taking up the lost motion in said mechanical means, is effective to continue such movement of said abutment relative to said port. 15

6. A valve structure, comprising a valve casing having a gas inlet chamber and a gas outlet chamber, inter-communication of which is effected by a port therebetween, a movable abutment in said casing and constituting a closure 20 for said port, said abutment being of greater area than said port and also constituting at least a part of a wall of said outlet chamber, the gas pressure on one face of said abutment constituting a varying force biasing said abutment for movement in port-opening direction, means constituting a constant force biasing said abutment for movement in port-closing direction, said constant biasing force being greater than the force of the gas pressure against that portion 25 of said abutment which constitutes a closure for said port, and mechanical means having a yieldable lost motion connection therein and operatively connected with said abutment for effecting, when actuated, limited movement of said 30 abutment relative to said port, and means for actuating said mechanical means, the parts being so constructed and arranged that when limited movement of said abutment relative to said port has been effected by actuation of said mechanical 40 means, one of said abutment biasing forces preponderates over the other and said preponderating force, by taking up the lost motion in said mechanical means, is effective to continue 45 such movement of said abutment relative to said port.

7. A structure as set forth in claim 1, characterized in that the lost motion connection of said mechanical means is of the pin and slot type and in that spring means are arranged on 50 opposite sides of said pin for yieldable engagement therewith.

OTTO J. KUENHOLD.
